US0D1045409S

(12) **United States Design Patent** (10) **Patent No.:** **US D1,045,409 S**
(45) **Date of Patent:** **** Oct. 8, 2024**

(54) **MIRROR**

(71) Applicant: **Dongguan Powerme Tech. Co., Ltd,**
Dongguan (CN)

(72) Inventor: **Guowei Yang**, Dongguan (CN)

(**) Term: **15 Years**

(21) Appl. No.: **29/936,652**

(22) Filed: **Apr. 9, 2024**

(51) LOC (14) Cl. **06-07**

(52) U.S. Cl.

USPC **D6/308**; D6/300

(58) **Field of Classification Search**

USPC D6/300, 308, 310, 312; D14/341;
D28/64.2, 64.3

CPC A45D 42/00; A45D 42/10; A45D 42/16

See application file for complete search history.

(57) **CLAIM**

The ornamental design for a mirror, as shown and described.

DESCRIPTION

FIG. 1 is a perspective view of a mirror showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the mirror, shown in a close configuration.

The dash-dash broken lines in the drawings depict portions of the mirror that form no part of the claimed design.

1 Claim, 9 Drawing Sheets
